DESIGN FOR A SHIELD.

No. 38,391.

Specification for Design.

Patented Jan. 1, 1907.

Application filed November 30, 1906. Serial No. 345,844. Term of patent 7 years..

To all whom it may concern:

Be it known that I, WILLIAM C. CODMAN, a subject of the King of Great Britain, residing at Providence, in the county of Providence and State of Rhode Island, have invented a new, original, and ornamental Design for a Shield, of which the following is a specification, reference being had to the accompanying drawing, forming part thereof.

The figure in the drawing represents the face view or obverse side of a shield, showing my new design.

I claim—

The ornamental design for a shield, as shown.

WILLIAM C. CODMAN.
